UNITED STATES PATENT OFFICE.

LUKE S. MILLS, OF NEW YORK, N. Y., AND CHARLES HART SMITH, OF BALTIMORE, MARYLAND.

IMPROVED ROOFING FOR BUILDINGS.

Specification forming part of Letters Patent No. 40,542, dated November 3, 1863.

To all whom it may concern:

Be it known that we, LUKE S. MILLS, of the city, county, and State of New York, and CHARLES HART SMITH, of Baltimore, in the State of Maryland, have invented a new and Improved Roofing for Buildings; and we do hereby declare that the following is a full, clear, and exact description thereof, reference being had to the accompanying drawings, and to the letters of reference thereon, making a part of this specification, in which—

Figure 1 is a sectional view, and Fig. 2 is a view of the top of partially-finished roof, the finished part extending as far as is covered by the part marked C C.

The subject of our invention is a roofing composed of an under layer of felt or sheathing-paper and a top layer of slate, tile, or other rigid substance, the two being connected and firmly held together by an intermediate layer of cement.

In order to enable others skilled in the art to make and use our invention, we will describe its construction.

We first cover the boarding of the roof D in Fig. 1 with sheathing-paper or felt, (represented by A,) attaching it to the roof in any convenient manner. The strips of paper or felt should overlap, leaving but one third of each exposed. We next take cement, composed of asphalt or coal-tar, from which its volatile elements have been expelled by boiling or distillation, and having made it fluid

by heat spread it evenly over the paper or felt. While the cement is yet soft we place upon it slate or tile or any other rigid material, bringing the different pieces near but not close to each other, and allowing the cement to fill the interstices. The cement, becoming hard by cooling, firmly connects the felt or paper with the rigid material.

We do not claim the manner of laying the felt, nor do we confine ourselves to the method above described.

The cement may be of asphalt, coal-tar, pitch, or any similar substance, or petroleum, or of two or more of them combined.

The slate or tile is represented in the drawings by C C. In the view of the top of the finished part of the roof, the tile or slate only of course are visible.

What we claim as our invention, and desire to secure by Letters Patent, is—

A roofing composed of a lower layer of felt or sheathing-paper and a top layer of some rigid substance, the two being firmly connected by an intermediate layer of cement.

LUKE S. MILLS.
